UNITED STATES PATENT OFFICE.

LUDVIG T. PETERSEN, OF YOUNGSTOWN, OHIO.

GOLF-BALL.

1,185,432.

Specification of Letters Patent.

Patented May 30, 1916.

Application filed February 21, 1916. Serial No. 79,648.

To all whom it may concern:

Be it known that I, LUDVIG T. PETERSEN, a citizen of the United States, residing at Youngstown, in the county of Mahoning 5 and State of Ohio, have invented certain new and useful Improvements in Golf-Balls; and I do hereby declare the following to be a full, clear, and exact description of the invention, such as will enable others 10 skilled in the art to which it appertains to make and use the same.

My present invention relates to the manufacture of resilient balls, but has reference more especially to balls which are designed 15 and adapted for use in playing the game of golf, or other games employing balls of similar character.

In the manufacture of balls embodying this invention it should be understood that 20 balata-gum is largely used as a basic material, but at the same time it should be understood that this invention is broad enough to include as a substitute for balata any substance or gums having like physical 25 characteristics, and to all such I lay claim the same as if herein specified. The term "balata" therefore as it appears hereinafter, and in the claims of this application, will be understood to include any substance pos- 30 sessing contractile qualities capable of first being rendered latent by stretching, then formed into substantially a spherical body, then heated to restore its latent contractile properties, and finally shaped under pres- 35 sure into the desired form and surface config- 40 uration. It is also understood by persons familiar with balata and similar gums of the gutta group, that when sheeted or cal- 45 endered it is characterized by a grain run- ning parallel with the length of such sheets; that it is stretchable at right angles to this grain but substantially inelastic when so stretched, and that after stretching, its contractile properties may be restored by the 50 application of heat thus rendering it elastic.

One object of the present invention is to provide balls for the use first above indicated, and other uses, possessing unusual 55 strength and durability, a high degree of resiliency, true spherical form, uniformity and compactness of structure, accurate bal- 60 astic properties, and a confined homogeneous internal strain.

A further object of the invention is the 65 production of over wound or built-up core-

less, seamless and resilient ball bodies, having retaining covers also of seamless and resilient material, capable of resisting and safely confining the expansive pressure, or homogeneous strain of the within contained 60 ball-body, and at the same time capable of instantly recovering normal spherical form after momentary distortion caused by the blow of a golf stick, or by other means.

Other objects and advantages of this in- 65 vention will be apparent to persons skilled in the art to which it relates, and the invention will be hereinafter particularly de- 70 scribed, and then pointed out in the claims following.

In the accompanying drawings which 75 form part of this application for Letters Patent, and whereon like characters refer to corresponding parts in the several views: Figure 1 is a transverse sectional view of the present invention taken centrally through a ball-body and the outer cover thereof. Fig. 2 is a perspective view showing a ball-body in the process of formation. Fig. 3 is also a perspective view showing 80 a ball-body cut in half for the purpose of illustrating its inherent expansive properties, and the effect thereof when not con- 85 fined by an outer cover, and Fig. 4 is a side elevation of a completed golf ball, in this instance a "bramble" surface configuration having been shown for example.

Reference being had to the drawings and numerals thereon, 1 indicates a laminated strip, strips or pieces of sheeted balata and 90 uncured india rubber, the latter 1^a in un- stretched condition being interposed be- 95 tween two similar strips of balata 1^b, 1^b during the process of calendering. After alternate sheets of balata rubber and balata have thus been calendered or rolled together into relatively thin sheets, it is customary to 100 cut said laminated sheets into strips at right angles to the grain of said sheets. In car- 105 rying out my present invention the said laminated strips comprising balata strips 1^b, 1^b and the interposed rubber strip 1^a, are first stretched longitudinally to practically the elastic limit of said balata strips, there- 110 by rendering latent their inherent contractile qualities and placing the interposed rubber strip 1^a under tension. An exceedingly small nucleus 2 is thereupon rolled at one end of the first of said laminated strips, and upon this as a center is built a coreless

ball-body from a succession of strips or pieces 1, each being first stretched as stated, and overwound one upon the other as indicated in Fig. 2, until approximately the desired size, weight, and spherical form has been produced. This accomplished the ball-body is next subjected to a mild degree of heat from any suitable source and by any suitable means, whereby the latent contractile qualities of the balata strips 1^a and 1^b are excited, stimulated and restored, causing a radial expansion of the ball body in an outward direction, and rendering it as a whole, when confined within a suitable cover 3, peculiarly resilient and responsive in long drives, and at the same time comparatively dead to light delicate blows as in putting. This restoration of the contractile properties of balata strips 1^a, 1^b—coacting with the elasticity of stretched rubber strips 1^a—is essential to the production of superior balls, but it is by no means necessary that it shall take place at the time and stage of manufacture above indicated, on the contrary the heating is equally effective, and in some instances more so, when applied at frequent intervals during the formation or winding of the ball-body.

The body of my present ball having been thus built up from laminated strips of balata and rubber wound and overwound, crossed and recrossed as shown by Fig. 2 of the drawings, is next incased within the outer seamless resilient cover 3 aforesaid, which by preference, is made in like manner as the ball-body from strips 1 applied and treated as aforesaid. In case of the cover 3, however, the balata employed should be refined to extract its naturally dark color, and prepare it for final coloring, the same being true of gutta-percha or celluloid when used as an outer casing.

Ball-body and cover, the latter of any suitable material, having been produced substantially as above indicated and of substantially spherical form, are next subjected to pressure in suitable molds heated to render the material slightly plastic, and are then compressed to a degree which insures true spherical form, causes the ball to automatically adjust its center of gravity to correspond exactly with its center of symmetry, and produces a suitable surface configuration such as the well known "bramble" design, which in the present drawings is used merely as an example. The completed ball is then permitted to cool slowly, and its cover to set before removal from the mold, after which it is finally coated or colored in the well understood manner.

The foregoing is a description of my present invention in its best form of embodiment at present known to me, but at the same time it should be understood that I by no means limit myself to the particular ar-

rangement and combination of elements set forth. On the contrary, various changes may be made and equivalent materials employed without in the least departing from the principle involved of utilizing balata or other gums of the gutta group, in laminated relation with cured rubber as a base. Stretching such balata or like material to first render its contractile properties latent, overwinding such laminated strips including balata or like materials, into substantially spherical form, and heating either at intervals in the course of winding, or after practically all strips have been applied, to stimulate or restore the latent contractile properties of the balata or like materials, thereby producing a cumulative internal pressure.

In conclusion, it may be noted that balls made according to the present invention have been found more satisfactory and efficient than balls made from balata only, for the reason that when supported and backed by an elastic material such as cured rubber 1^a, the laminated strips of balata 1^b are capable of being drawn or calendered much thinner than would be possible if unsupported, and as a consequence this has been found to materially increase the contractility of the said balata strips, and proportionally increase the internal pressure of the ball-body when subjected to heat substantially as shown and described.

Having thus described my present invention, what I now claim and desire to secure by Letters Patent is:

1. As an article of manufacture a resilient ball-body made from overwound strips of cured rubber under tension and previously stretched balata in which latter the contractile qualities rendered latent by stretching have been restored after winding.

2. As an article of manufacture a resilient ball made from overwound strips of cured rubber under tension and previously stretched balata in which latter the contractile qualities rendered latent by stretching have been restored subsequent to winding, in combination with a ball cover of like materials.

3. As an article of manufacture a resilient ball-body made of alternate strips of cured rubber under tension and previously stretched balata in which latter the contractile qualities rendered latent by stretching have been restored after winding.

4. As an article of manufacture a resilient ball made of laminated strips which comprise cured rubber under tension and previously stretched balata in which latter the contractile qualities rendered latent by stretching have been restored after winding.

5. As an article of manufacture a resilient ball made of overwound strips of cured rubber laminated with corresponding strips

of previously stretched balata in which latter the contractile qualities rendered latent by stretching have been restored subsequent to winding.

6. A golf ball made from overwound composite strips of cured rubber and balata under tension in which strips the contractile qualities of the balata rendered latent by

stretching have been restored subsequent to winding.

In testimony whereof I affix my signature, in presence of two subscribing witnesses.
